United States Patent Office

Des. 184,452
Patented Feb. 17, 1959

184,452

WHEEL COVER

Ned F. Nickles, Detroit, Mich., assignor to General
Motors Corporation, Detroit, Mich., a corporation of Delaware

Application February 13, 1958, Serial No. 49,633

Term of patent 7 years

(Cl. D14—30)

I claim:

The ornamental design for a wheel cover, substantially as shown.
